WHEEL COVER

Donald D. Hoagg, Birmingham, Mich., assignor to General Motors Corporation, Detroit, Mich., a corporation of Delaware

Application December 10, 1956, Serial No. 44,146

Term of patent 7 years

(Cl. D14—30)

I claim:

The ornamental design for a wheel cover, substantially as shown.
